J. J. BECKER

MECHANICAL TOY

Filed Dec. 22, 1925

INVENTOR.
John J. Becker
BY Samuel O. Alworth

ATTORNEY.

UNITED STATES PATENT OFFICE.

JOHN J. BECKER, OF BROOKLYN, NEW YORK.

MECHANICAL TOY.

Application filed December 22, 1925. Serial No. 76,952.

My invention relates to mechanical toys and more particularly to that class of toys in which a travelling carriage in its movement carries and actuates a horizontally disposed rotor or rotatable member, which, at its periphery is provided with dependent swinging arms having ball like ends so that by the rotation of the rotor the arms are actuated by centrifugal force and displaced radially outward by means actuated by the carriage movement.

Some of the objects of my invention are, to provide a toy of this type which is of simple and durable construction, of comparatively few parts, of pleasing and artistic appearance, of educational value, and which may be a source of instruction or amusement to children and adults.

Another object is, to provide a toy of this type in which the movable parts and pendant arms are so colored that when actuated they will produce an optical effect resembling a blended ring or rings of color or colors.

Another object is, to provide a toy of this character of such construction that it may be conveniently assembled or disassembled for repair or transportation in containers and effectively supported for travelling movement.

Another object is, to provide a toy in which, when the rotor is actuated, the arms shall be caused to swing outwardly to simulate or suggest the movement of objects in restrained flight.

Another object is, to provide a toy of such construction that it will have long life under ordinary usage, be exceedingly durable, not readily broken, positive in its operation and have other advantages and results which may hereinafter appear.

Another object is, to provide a toy in which a rotor having swinging pendant arms is actuated by the movement of a carriage, by means of driving mechanism supported by the carriage and adapted to transmit to the rotor the rotary movement of the carriage wheels when the carriage travels.

Another object is, to provide a device of this type in which a rotor is so disposed and actuated that pendant swinging arms carried on the periphery thereof will be actuated by centrifugal force and thereby be thrown radially outward to positions of ele-

vation which vary with the speed of the travelling movement of the carriage.

My invention consists in the particular construction, combination, organization and arrangement of parts shown in the accompanying drawings, described in the specification and more particularly pointed out in the appended claims.

In the accompanying drawings:

Fig. 1 is a side elevation of my invention, partly in cross section, with some parts broken away, showing the assembled relation of the parts and the means for actuating the rotor by the movement of the travelling carriage.

Fig. 2 is a top plan view of the rotor, illustrating its formation and assembly of the pendant arms therewith.

Referring more particularly to the drawings, in which like numerals of reference indicate corresponding parts, my device comprises a base 10, provided near each end with axles 11 and 12, which extend through the base 10 from side to side and at least one of which, preferably 11, is rotatable in the base. Wheels 13 and 14 to support the carriage in its travelling movement are mounted on the axles 11 and 12, and the wheels 14 may be loosely mounted on the shaft 12 and held against displacement therefrom by cotter pins 15 or any other suitable means. The wheels 13 are fixed to shaft 11, so that when the carriage 10 is caused to travel and the wheels 13 rotate the shaft 11 will be rotatably driven thereby.

Below the body 10 of the carriage, affixed to the shaft 11, substantially midway its length and rotating therewith when the carriage is caused to travel, is a bevel gear 16. The gear 16 meshes with a co-acting bevel gear 17, which is carried at one end of the shaft 18, which latter is rotatably mounted in brackets or hangers 19 and 20, affixed to and extending beneath the body of the carriage 10. The shaft 18, substantially intermediate its length, is provided with a bevel gear 21, so arranged that it may be adjusted lengthwise on shaft 18, but which turns with said shaft when the carriage travels and which is adapted to transmit the rotary motion of the wheels 13 to means connected with a rotor, hereinafter to be described.

The shaft 18, at the end opposite that

carrying the bevel gear 17, is provided with an adjustable collar 22, having a set screw 23 or other suitable holding means to hold the collar in adjusted position, so that the 5 collar will properly position the shaft 18 and cause the gears 16 and 17 to mesh in proper operative relation.

An upwardly extending post or standard 10 24 is carried by and fixed to the upper surface of the carriage body 10 by clinch pins 25, or other suitable fastening means, that engage the base of the standard and hold it in fixed relation to the carriage body. The post or standard 24 is provided with a substantially 15 central tubular portion or chamber 26, extending substantially its entire length which, near its bottom end, has an enlarged section 27 and at its upper end a section 28 of lesser diameter than the main body portion of the tubular chamber 26. At the upper end of the post or standard 24 a substantially circular eyelet 29 is partially inset into the post or standard 24 so that it projects above the level of the surface 20 of the upper end thereof and is concentric with the tubular portion 28 of the chamber 26.

A vertical rotatable shaft 30 extends longitudinally through the post or standard 24 and is encased in the chamber 26, terminating at its lower end beneath the body 10 of the carriage and at its upper end projecting a suitable distance above the top of the post 24. The shaft 30 is provided with an adjustable collar 31, which rests upon the eyelet 29 and thereby provides a support or bearing upon which shaft 30 may rotate when actuated. Near its lower end the shaft 30 is also provided with an adjustable collar 32 40 encased within the enlarged lower end portion 27 of the chamber 26, so that the shaft 30 may be retained in its proper operative position.

At the lower end of the shaft 30 there is mounted a bevel gear 33, in fixed relation to the shaft 30 rotating therewith and adapted to mesh with the bevel gear 21 of the shaft 18. When the carriage travels, the bevel gear 16 will rotate and by means of the bevel gear 17 will rotate the shaft 18, which in turn will rotate the bevel gear 21, and the latter, meshing with the bevel gear 33, will cause the bevel gear 33 to rotate and will thereby effect the rotation of the upright vertical shaft 30. The diminished section 28 of the upper portion of the chamber 26 in the standard or post 24 is of such size that it will afford a bearing for that portion of the shaft 30 which it surrounds and engages 50 and will thereby effect a proper operative positioning of the shaft 30 and the desired operative relation to these parts.

Carried on and fixed to the upper end of the vertical shaft 30 is a substantially disc 60 like rotor 34, adapted to be carried by the

shaft 30 and rotated thereby when the carriage travels. The disc like rotor 34 is shown to be of slightly convexed formation and circular shape but it may be constructed of any suitable or desired shape and formation that will permit its being carried and rotated by the vertical shaft 30. Around the periphery of the rotor 34 is provided a series of radially disposed in cut or recessed sections 35, between which sections the outer peripheral edge of the rotor is downwardly and inwardly bent to form a tubular margin or edge 36. Carried by and enclosed in the tubular margin or edge 36 is a split ring 37, extending substantially completely around the under side of the peripheral edge of the rotor, so that the outer open portion of the in cut sections 35 are each bridged by a portion of the ring 37. In each of the in cut sections 35 of the rotor, one of a series of depending arms 38 is swingably mounted on portions of the split ring 37 which bridge the open end of each of the in cut sections 35. These depending arms 38 are provided, at their lower ends, 70 with enlarged ball like members or balls 39 and at their upper ends with an enlarged substantially conical shaped stop member 40. The ball like members 39 serve as weights to normally retain the depending arms 38 in substantially vertical position, as shown in Fig. 1, depending from the rotor 34 when the carriage is stationary and the rotor is not being rotated. When the carriage is caused to travel and the wheels 13 rotate, 75 the shaft 11 will be rotated and the bevel gear 16, rotating with the shaft 11 and meshing with the bevel gear 17, will rotate the shaft 18 and the vertical shaft 30 will thereby be rotated by the bevel gear 21 meshing with the bevel gear 3 on the shaft 30 and the rotor 34 carried at the top of the shaft 30 will thereby be caused to rotate. The depending arms 38, when the rotor is thus rotated will, by the action of centrifugal force, tend to be thrown radially outward to a greater or lesser degree of elevation as shown in dotted lines in Fig. 1, 80 until, if the speed of rotation of the rotor is sufficiently increased by the increased speed of movement of the carriage, the arms 38 will assume a substantially horizontal position, as shown in the topmost pair of dotted lines in Fig. 1.

In order to limit the height to which the arms 38 may be thrown by the travel of the carriage and the rotation of the rotor 34, conical shaped stop members 40 are provided on the upper end of the depending arms 38 of such shape and size that when the arms 38 are, by the movement of the carriage, elevated to the desired predetermined degree, the members 40 will contact with the opposite edges of the in cut peripheral sections 35 of the rotor and provide a stop, to limit fur- 85 90 95 100 105 110 115 120 125 130

ther elevation of the arms, as is shown in the dotted lines in Fig. 1.

Each of the depending arms 38 is provided near its upper end with a transverse opening 5 extending diametrically through the body of the arms, to receive and thereby be swingably carried upon the portions of the split ring 37 which bridge the incut sections 35 of the rotor 34. The arms 38 are thereby so suspended that they are permitted a free swinging movement inwardly and outwardly, radially, as the rotation of the rotor decreases or increases with the change in speed of the movement of the carriage, but are prevented 10 any substantial lateral swinging movement which might otherwise interfere with the intended operation of my device.

The travelling movement of the carriage may be effected by pushing or pulling it, so 20 that the wheels 13 will rotate and, as described, actuate the rotator 34 and effect the outward radial displacement of the swinging arms 38. To facilitate this travelling movement I provide at one end of the body 10 of 25 the carriage a sliding arm 42, which is supported in a slot 43 at one end of the body 10 and which, at its inner end, has an angularly bent portion 44 adapted to engage the stop 45 carried on the underside of the carriage body 30 10. This arm 42 is so mounted that it can slide backwardly and forwardly a limited distance, so that when desired it may be retracted with its outer end 46 abutting against the end of the carriage body 10 and offer substantially no obstruction to a convenient and 35 compact packing of the device in a suitable container while, at the same time, it may be drawn outwardly as shown in Fig. 1 when it is desired to cause the carriage to travel by 40 means of pulling force, which may be exerted on a cord or other suitable means, not shown, but which may be attached to the outer end 46 of the arm 42. The arm 42 is provided to slide outwardly, as shown in Fig. 1, so that 45 when the carriage is pulled, as described, and the depending arms are thrown outwardly by centrifugal force, as the carriage travels, the arms will be free to swing without coming in contact with the pulling cord.

50 The collars 31 and 32 on the shaft 30 on the upper and lower ends respectively of the post or standard 24 are arranged to be adjustable longitudinally on the shaft 30, in order that the shaft may be given the proper 55 position of vertical elevation to enable the gear 33 to properly mesh with the bevel gear 21 and effect the desired rotation of the rotor 34.

In the formation of my device as shown in 60 Fig. 1 I prefer to construct the carriage body 10 and the brackets 19 and 20 and the other actuating transmitting mechanism of metal or other suitable materials, while the wheels, upright standard or post 24, the depending 65 arms 38, the balls 39 and the cone shaped stop

members 40, I prefer to construct of wood or other suitable material, although it is obvious that any suitable material may be employed in the construction of the respective parts of my device.

I also create a novel optical color effect when the rotor is operating, by variously coloring the visible moving parts of my device, particularly the rotor 34, the arms 38, the balls 39 and the stop members 40.

The operation of my device is as follows:— The carriage is caused to travel by being pulled, for instance, by means attached to the bar 42, the wheels 13 will rotate and rotate the axle 11, which will thus cause the bevel gear 16 carried thereon to rotate. The gear 16, meshing with the gear 17, will rotate the shaft 18 and the bevel gear 21 mounted thereon. The bevel gear 21 thus rotating and meshing with the bevel gear 33 will rotate 80 the shaft 30 and cause the rotor 34 carried thereon and rotating therewith, to rotate.

As the speed of travel of the carriage increases the depending arms 38 will swing upon the supporting split ring 37 and be thrown 90 radially outward, by the action of centrifugal force, until the outward swing of the arms 38 has been stopped by the contact of the conical stop 40 with the edge of the incut sections 35 in the periphery of the rotor 34. As the 95 speed of travel of the carriage decreases the action of the centrifugal force will decrease and the swinging arms 38 will swing inwardly under the force of gravity, until at the cessation of travel of the carriage they will 100 assume the pendant position shown in Fig. 1.

By means of the adjustable relation to each other of the power transmitting elements of my device, my apparatus is peculiarly adapted to sure and positive operation when 105 desired. By means of the peculiar construction, assembly and organization of the parts of my device I have produced an apparatus which can be readily assembled and readily disassembled and which may be packed in a 110 compact shape for transportation, which is of durable construction and which may be readily repaired.

Although I have thus described my invention in detail and specifically illustrated it 115 in the accompanying drawings, I do not wish to be limited to the particular form of embodiment shown, nor by the term of description defining it, except as the state of the art and the appended claims may require, for it is obvious that various modifications may be made in the combination, organization, and arrangement of parts of my invention, without departing from the spirit and scope thereof.

Having thus described my invention in detail, what I claim as new and desire to secure by Letters Patent is:

1. In a mechanical toy, the combination of a travelling carriage, rotatable wheels 130

supporting said carriage a rotatable axle carried and actuated by one pair of rotatable wheels, a vertical shaft rotatably mounted on and extending above said carriage, a rotor mounted above said carriage on said shaft adapted to be rotated thereby in a horizontal plane and having a series of radially incut sections at the periphery thereof, a series of independent arms depending from said rotor, the same being pivotally mounted in said incut sections and adapted to swing radially outward therefrom, members integral with and fixed to the free ends of said radial arms and being of greater diameter than the diameter of the arms, and rotating means connecting said axle and said vertical shaft adapted to transmit the rotary motion of said axle to said vertical shaft and rotor and effect the rotation of said rotor and the radial outward swinging of said depending arms.

2. In a mechanical toy, the combination of a travelling carriage, rotatable wheels supporting said carriage, a rotatable axle carried and actuated by one pair of rotatable wheels, a vertical shaft rotatably mounted on and extending above said carriage, a rotor fixed to and carried by said vertical shaft above said carriage adapted to be rotated thereby in a horizontal plane, a series of independent arms depending from the periphery of said rotor adapted to swing radially outward therefrom, ball-like members integral with and fixed to the free ends of said radial arms, stop means on said radial arms cooperating with said rotor adapted to limit the outward swing of said arms and rotating means connecting said axle and said vertical shaft adapted to transmit the rotary motion of said axle to said vertical shaft and effect the rotation of said rotor and the radial outward swinging of said depending arms.

3. In a mechanical toy, the combination of a travelling carriage, rotatable wheels supporting said carriage, a rotatable axle carried and actuated by one pair of rotatable wheels, a vertical tubular standard fixed to and extending above said carriage, a vertical shaft rotatably mounted on and extending above said carriage incased within and supported by said standard, a rotor fixed to and carried by the upper end of said vertical shaft adapted to be rotated thereby in a horizontal plane, a series of independent depending arms mounted on the periphery of said rotor adapted to be swung radially outward therefrom, ball like members fixed to and integral with said arms disposed at the lower ends thereof, stop members fixed to and integral with said arms disposed at the upper ends thereof, a gear adapted to rotate said vertical shaft and fixed to the lower end thereof, a gear fixed to and adapted to rotate with said axle dis-

posed intermediate said rotatable wheels and gear means connecting said axle gear and said vertical shaft gear adapted to transmit the rotary motion of said axle to said vertical shaft and gear thereon and thereby effect the rotation of said rotor and the radial outward swinging of said depending arms.

4. In a mechanical toy, the combination of a travelling carriage, rotatable wheels supporting said carriage, a rotatable axle carried and actuated by one pair of rotatable wheels, a vertical tubular standard mounted on and extending above said carriage, journal bearings in the upper and lower ends of said vertical standard, a vertical shaft mounted on and extending above said carriage incased within said tubular standard and rotatably supported in said journal bearings, a rotor fixed to and carried by the upper end of said vertical shaft adapted to be rotated thereby in a horizontal plane, a series of radially incut sections disposed around the periphery of said rotor, a series of depending arms mounted at the periphery of said rotor in said incut sections adapted to be swung radially outward from said rotor, ball like members fixed to and integral with said arms disposed at the lower ends thereof, stop members fixed to and integral with the said arms disposed at the upper ends thereof, co-operating with said incut sections, a gear adapted to rotate said vertical shaft and fixed to the lower end thereof, a gear fixed to and adapted to rotate with said axle, brackets carried by said travelling carriage and depending therebelow, an adjustable shaft rotatably mounted in said brackets, a gear on said shaft meshing with the vertical shaft gear and a gear near the other end of said shaft meshing with said axle, gear adapted to transmit the rotary motion of said axle to said vertical shaft and gear thereon and thereby effect the rotation of said rotor and the radial outward swinging of said depending arms.

5. In a mechanical toy, the combination of a travelling carriage, rotatable means supporting said carriage, a rotatable axle carried and actuated by said rotatable means, a gear fixed to and rotated by said axle, an upwardly extending vertical shaft mounted on said carriage, a gear fixed to the lower end thereof and adapted to rotate said shaft, an upwardly extending vertical tubular standard adapted to support said vertical shaft in operative position, means on said vertical shaft adapted to vertically adjust said shaft in relation to said standard, a rotor fixed to the upper end of said shaft and adapted to be rotated thereby, in a horizontal plane, a series of radially disposed incut sections around the periphery of said rotor, supporting means carried by

said rotor conforming to the periphery thereof and spanning the radially disposed in-cut sections, a series of arms disposed within said in-cut sections mounted on said supporting means and adapted to swing radially outward from the periphery of said rotor, ball like members at the lower end of said arms integral therewith, stop members at the upper end of said arms integral there-
10 with adapted to co-operate with said in-cut sections and limit the outward swinging of said arms, an adjustable rotatable shaft disposed beneath said travelling carriage adapted to rotatably support said shaft and
15 gears carried by said shaft adapted to engage said gear on said vertical shaft and said gear on said axle and transmit the rotary motion to said axle, to said vertical shaft and rotor and thereby effect the rotation of said rotor and the radial outward swinging of said depending arms.

6. In a mechanical toy, a traveling carriage, rotatable wheels supporting said carriage, rotatable means actuated by a pair
20 of said wheels including a vertical shaft extending above the carriage, means for supporting said shaft on the carriage, a disk fixedly secured to the upper end of the shaft

to rotate therewith and spaced from said shaft supporting means, and a series of independent means pivotally attached to and depending from said disk and adapted to be swung outwardly upon rotation of said disk, the arms each having an enlargement at its upper end for engagement with the disk to limit the outward swing of the arms. 30 35

7. In a mechanical toy, a traveling carriage, rotatable wheels supporting said carriage, rotatable means actuated by a pair of said wheels including a vertical shaft 40 extending above the carriage, means for supporting said shaft, a disk fixedly secured to the upper end of said shaft to rotate therewith, the disk having in-cut sections at its periphery, and a series of independent arms 45 pivoted at the upper ends in said sections of the disk, the arms each having an enlarged lower end and also an enlarged upper end, the latter being adapted to engage the disk to limit the outward swing of the arms. 50

Signed at the borough of Brooklyn, city of New York, in the county of Kings and State of New York, this 21st day of December A. D. 1925.

JOHN J. BECKER.
